CLAIM

The ornamental design for a rivet or the like, as shown and described.

DESCRIPTION

FIG. 1 is a top plan view of a rivet or the like, showing my new design;

FIG. 2 is a front elevational view thereof;

FIG. 3 is a bottom plan view thereof;

FIG. 4 is a side elevational view taken from the right of FIG. 3;

FIG. 5 is an enlarged cross-sectional view taken in the direction of the arrows on line V-V of FIG. 3;

FIG. 6 is an enlarged cross-sectional view similar to FIG. 5 but in the position of use.
